UNITED STATES PATENT OFFICE.

CARL FREDRICK MAGNUSSON, OF MINNEAPOLIS, MINNESOTA.

ADJUSTABLE WINDOW CURTAIN AND SHADE HOLDER.

1,425,996.

Specification of Letters Patent. Patented Aug. 15, 1922.

Application filed March 9, 1921. Serial No. 451,075.

To all whom it may concern:

Be it known that I, CARL FREDRICK MAGNUSSON, a citizen of the United States, residing at Minneapolis, in the county of 5 Hennepin and State of Minnesota, have invented certain new and useful Improvements in Adjustable Window Curtain and Shade Holders; and I do hereby declare the following to be a full, clear, and exact description of the invention, such as will enable others skilled in the art to which it appertains to make and use the same.

My invention has for its object to provide an extremely simple and highly efficient adjustable window curtain and sash holder, and to this end, it consists of the novel devices and combinations of devices, hereinafter described and defined in the claim.

In the accompanying drawings which 20 illustrate the invention, like characters indicate like parts throughout the several views.

Referring to the drawings:

Fig. 1 is a perspective view showing the 25 improved window curtain and sash holder applied to the casing of a window frame and having supported thereon a curtain rod and shade by means of broken lines;

Fig. 2 is a right hand elevation of the 30 parts shown in Fig. 1; and

Fig. 3 is a fragmentary detail view with some parts sectioned on the line 3—3 of Fig. 1.

The numeral 4 indicates a window frame 35 in which are mounted upper and lower sashes 5 and provided with a casing 6, in the upper corners of which, are blocks 7 which extend outward of the casing proper.

The invention includes two flat plates 8, 40 the upper portions of which, as shown, bear against the outer faces of the blocks 7 and the lower portions of which are inwardly offset and bear against the outer faces of the stiles of the casing 6. On the outer edges of the casing plates 8 are upper, lower and intermediate inturned ears 9 arranged to engage with the outer edges of the blocks 7 and the casing stiles 6. Formed with the outer edges of the casing plates 8, 45 above the upper ears 9, is a pair of outwardly projecting arms 10 having, in their upper edges, open seats 11, to receive and hold a curtain rod 12 indicated by broken lines.

50 Secured to the casing plates 8, just below the intermediate ears 9, is a pair of hori-

zontally aligned channels 13, the flanges of which at their free edges, are bent laterally inward to afford a pair of retaining flanges 14. Slidably mounted in the channels 14 60 is a pair of roller supporting brackets 15, one of which is provided with a round hole 16 to receive the trunnion 17 of an ordinary shade roller 18, and the other of which, is provided with an open seat or notch 19 65 to receive and hold the flattened end of the ratchet rod 20 of said roller. Secured to the roller 18 is a shade 21 indicated by broken lines.

The casing plates 8 are held in position 70 without the use of screws, nails or other means that would mar the woodwork, by a pair of aligned rods 22 which extend along the outer faces of the casing plates 8 and are anchored to the stiles of the casing 6 75 by bending the outer portions of said casing plates. The free ends of the rods 22 are bent at the shoulders 23 into parallel arrangement with the bodies of said rods to afford a pair of barbs 24. These barbs 24 80 extend through holes 25 in the intermediate ears 9 and are adapted to be pressed into the underlying portions of the stiles of the casing 6 to anchor said rods thereto.

The inner ends of the rods 22 are bent 85 to afford hooks 26 to which are attached the ends of a coiled spring 27. This spring 27 is under strain to draw the rods 22 endwise toward each other and thereby hold their barbs 24 pressed into the stiles of the 90 casing 6 with their shoulders 23 bearing against the intermediate ears 9 and thereby drawing the casing plates 8 toward each other with all of the ears 9 pressed against the outer edges of the stiles of the casing 6 95 and blocks 7. The rods 22, by extending along the outer faces of the casing plates 8, hold the same flat, against the stiles of the casing 6 and blocks 7. By extending the barbs 24 through the intermediate ears 9, 100 the casing plates 8 are held against downward movement on the stiles of the casing 6 and the offset portions of said casing plates 8, by their engagement with the lower edges of the blocks 7, properly position said 105 casing plates.

In case the casing is not provided with corner blocks that extend outward thereof, the casing plates may be made flat throughout their entire length. Obviously, the 110 spring 27 will adjust itself to windows of different widths and the shade brackets 15

may be adjusted in the channel 13 for different widths of windows and shades. It will be noted that each casing plate 8, ears 9 and arms 10 are all formed from a single sheet of metal.

The above described invention, while extremely simple and of small cost to manufacture, is thought to be highly efficient for the purpose had in view. Obviously, the 10 improved holder may be put up or taken down with very little work and will not mar or deface the woodwork.

What I claim is:

A holder of the kind described comprising 15 a pair of casing plates having shade

and curtain holding devices and also having smooth inturned ears adapted to frictionally engage outer edges of a casing, a pair of aligned rods extending across the outer faces of said plates and having barbed-equipped laterally bent ends, said barbed-equipped ends being extended through apertures in certain of said ears and adapted to be pressed into the respective edges of the casing, and a spring connecting said two 25 rods and under strain to draw the same toward each other.

In testimony whereof I affix my signature.

CARL FREDRICK MAGNUSSON.
